UNITED STATES PATENT OFFICE

112,301

DESIGN FOR A TEXTILE FABRIC

Samuel Golland, Brooklyn, N. Y.

Application October 17, 1938, Serial No. 80,515

Term of patent 3½ years

To all whom it may concern:

Be it known that I, Samuel Golland, a citizen of the United States and resident of 929 East 18th Street, Brooklyn, N. Y., in the county of Kings and State of New York, have invented a new, original, and ornamental Design for Textile Fabrics, of which the following is a specification, reference being had to the accompanying drawing, forming part thereof.

In the accompanying drawing, the figure is a plan view of the textile fabric, showing my new design.

I claim:

The ornamental design for a textile fabric, as shown.

SAMUEL GOLLAND.
